CLAIM

The ornamental design for a chemical tablet for aquatic systems, as shown and described.

DESCRIPTION

FIG. 1 is a perspective view of a chemical tablet for aquatic systems showing my new design;

FIG. 2 is a first side view of the chemical tablet for aquatic systems;

FIG. 3 is a second side view of the chemical tablet for aquatic systems;

FIG. 4 is a third side view of the chemical tablet for aquatic systems;

FIG. 5 is a fourth side view of the chemical tablet for aquatic systems;

FIG. 6 is a top view of the chemical tablet for aquatic systems;

FIG. 7 is a bottom view of the chemical tablet for aquatic systems

FIG. 8 is a perspective view of another embodiment of a chemical tablet for aquatic systems showing my new design

FIG. 9 is a side view of the chemical tablet for aquatic systems as shown in FIG. 8;

FIG. 10 is a bottom view of the chemical tablet for aquatic systems as shown in FIG. 8;

FIG. 11 is a perspective view of yet another embodiment of a chemical tablet for aquatic systems showing my new design;

FIG. 12 is a side view of the chemical tablet for aquatic systems as shown in FIG. 8; and,

FIG. 13 is a bottom view of the chemical tablet for aquatic systems as shown in FIG. 8.

The chemical tablet as shown in FIGS. 1-13 is intended to be placed in an aquatic system. Once placed in an aquatic system, the chemical tablet dissolves over time releasing one or more chemicals into the aquatic system.
